UNITED STATES PATENT OFFICE.

CHARLES LE G. FORTESCUE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL DEVICE.

Application filed October 24, 1917, Serial No. 198,278. Renewed August 12, 1921. Serial No. 482,182.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Electrical Devices, of which the following is a specification.

10 My invention relates to electrical devices and particularly to devices for improving the performance of electrical systems.

One object of my invention is to provide means for supplying energy to an electrical system from an auxiliary source of energy in proportion to the rate of dissipation of energy in the system.

Another object of my invention is to provide means whereby energy proportional to the energy dissipated in a circuit, by reason of the electrical or physical properties of the circuit, may be supplied to thereby increase the sensitiveness of the circuit.

Another object of my invention is to provide means whereby measuring instruments that are used in null methods of measurements may be adapted to have high-voltage-sensitivity under all conditions.

Another object of my invention is to provide means whereby the losses in an intelligence-transmission circuit that are caused by the physical and electrical characteristics of the circuit may be so supplied that the performance of long-distance circuits of this type may be materially improved.

Another object of my invention is to provide a constant-speed series-wound generator for so supplying predetermined losses in a circuit that the detrimental effects of such losses may be eliminated or varied in any desired manner.

A further object of my invention is to provide a device of the above-indicated character that shall be simple and inexpensive to construct and effective in its operation.

It is well known that the deflections of galvanometers that are used in Wheatstone bridges, and other similar null methods of measurements, are dependent upon the cur-

rent traversing the same. It is also well known that high-resistance instruments are desirable because of the sensitiveness of the same. Further, it is well known that, if the current traversing a long-distance telephone or telegraph circuit is unimpeded by reason of the physical and electrical characteristics of such circuits, more efficient and longer transmission may be obtained.

In view of the above, I provide a series-wound generator that is connected in series with the circuit the sensitiveness of which is to be increased. The generator is driven at a constant speed from an independent source of energy. If the generator is connected in series with a galvanometer of a Wheatstone bridge and is so designed that it will supply energy to the circuit proportional to the rate of dissipation of energy in the galvanometer circuit, it will constitute a negative resistance which, under all conditions, equals the resistance of the galvanometer. Thus, the galvanometer may be designed to have a relatively large number of turns and a maximum sensitiveness under all conditions of the test.

To further increase the sensitiveness of the device, the generator may be constructed with no iron in its magnetic circuit and enclosed in an iron casing to shield the same from the earth magnetic field.

If the series-wound generator is employed in an intelligence-transmission circuit, it is so designed that it supplies energy thereto from an independent source, proportional to the rate of energy dissipated by reason of the resistance of portions of the circuit. That is, a number of devices are connected in the circuit at predetermined points thereon, and, by such arrangement, all of the power traversing the circuit is caused to perform useful work. The generator is preferably constructed with no magnetic materials in its magnetic circuit and will thus readily respond to increasing and decreasing currents traversing the circuit without the errors incident to the hysteretic lag therein.

In the accompanying drawings, Figure 1 is a diagrammatic view of a Wheatstone

bridge embodying my invention; Fig. 2 is a diagrammatic view of an intelligence-transmission circuit embodying my invention; and Figs. 3 and 4 are views of intelligence-transmission circuits embodying modified forms of my invention.

In Fig. 1, a Wheatstone bridge 1 comprises resistors 2, across two of the terminals of which a source 3 of electromotive force is connected and across the other terminals of which a galvanometer 4 is connected. A series-wound generator 5, having a field-magnet winding 6, is connected in series with the galvanometer 4 and is adapted to be actuated by a shunt-wound motor 7 that is supplied with energy from the source 3 of electromotive force. The generator 5 and the motor 7 are disposed in a casing 8 of magnetizable material for the purpose of shielding the same from the influence of the earth magnetic field. The generator 5 is preferably constructed with no magnetic materials in its magnetic circuit in order that it may be equally responsive to increasing and decreasing currents traversing the same. If the generator 5 is provided and is actuated at a constant speed to generate energy that is proportional to the energy dissipated by reason of the resistance of the galvanometer 4, the galvanometer 4 may have a relatively large number of turns and be thus sensitive under all conditions. That is, the generator 5 may be considered a negative resistance, which is equal to the resistance of the galvanometer 4 and, therefore, permits a relatively large current to traverse the same for a small difference in potential between the points of application. Thus, very accurate balancing of the bridge 1 may be obtained, and a galvanometer, which is sensitive under all conditions, may be used.

In Fig. 2 of the drawings, an intelligence-transmission circuit 9, such as a telegraph circuit, comprises a source 10 of electromotive force, a key 11 and a receiving relay 12. If the resistance of the circuit 9 and the various transmitting and receiving apparatus therein can be compensated, all of the power traversing the same may be used to perform useful work. Also, in order that no attenuation and distortion shall obtain in the circuit, the transmission losses must be zero. In order to reduce the transmission losses that are caused by the resistance of the circuit 9, I provide, at predetermined intervals along the circuit 9, series-wound generators 13, substantially as hereinbefore set forth. The generators 13 are adapted to be driven by constant-speed motors 14 and are designed to generate energy that is proportional to the energy dissipated by reason of the resistance of that part of the circuit to which the same are connected. Thus, the generators 13 are adapted to supply energy, at all times, to the circuit 9 that is propor-

tional to the loss of energy in the circuit and, consequently, the transmission losses will be reduced to zero, and the total current that is used for signalling or communicating purposes is transmitted therethrough.

In Fig. 3 of the drawings, an intelligence-transmission circuit 15 comprises two conductors 16 and 17 having series-wound generators 18 and 19 therein at predetermined points. The generators 18 and 19 are adapted to generate energy in proportion to the energy dissipated by reason of the resistance of the respective portions of the circuit 15 and are driven at constant speed by shunt-wound motors 20 that are supplied with energy from sources 21 of electromotive force. By this arrangement, the working current that traverses the circuit 15 is not dissipated in the resistance of the circuit and may all be used in effective work. Consequently, the circuit 15 may be made relatively long, and the quality of the communication thereon may be greatly improved.

If it is desired to compensate for the leakage resistance in the circuit 15, reactance coils 22 are connected across the conductors 16 and 17 at predetermined points and the central points of the coils 22 are connected, through relatively small condensers 23, to ground. A series-wound generator 24 is connected in shunt relation to each of the condensers 23 and is so designed that it develops energy in proportion to the leakage energy through that portion of the circuit. The generators 24 are actuated at a constant speed by motors 25 that are supplied with energy from a source 26 of electromotive force. Since a plurality of grounding devices are used, the generators 24 are designed to supply only the loss of energy that is caused by the leakage loss in the particular portion of the circuit to which it is connected.

If it is desired to protect an intelligence-transmission circuit 27, such as shown in Fig. 4, from the detrimental effects of an extraneous circuit, such as a power transmission line (not shown), which induces currents of a different frequency in the same, I provide parallel resonant circuits 28 severally comprising a condenser 29, a serially connected inductor 30 and an inductor 31 connected in parallel to both the condenser 29 and the inductor 30. These resonant circuits are connected in series with the circuit 27 at predetermined points and are so tuned as to carry circulating currents of only the frequency of the power-transmission line or other extraneous circuit, whereby said currents are prevented from flowing in the intelligence-transmission line. A series-wound generator 32 is connected in circuit with each of the resonant circuits 28 and is adapted to generate energy in accordance

with the circulating current in the resonant circuits in order to overcome the effect of resistance therein. Thus, the energy that is dissipated in the resonant circuits and which is induced in the circuit 27 by neighboring transmission lines may be compensated for, and the resistance to the flow of current through the circuit 27 may be materially reduced.

10 When it is not necessary to protect the circuit 27 from adjacent transmission lines, the inductance of the generators 32 may be used for the same purpose as the well known Pupin coils. However, when it is desired 15 to supply the energy that is dissipated in the resonant circuits, the generators do not function to change the phase-angular relation of the current traversing the circuit. Other resonant circuits 33 may be connected, 20 at predetermined points, between the conductor 27 and ground to filter currents of objectionable frequencies out of the circuit. The circuits 33 may be provided with series-wound generators 34, as hereinbefore set 25 forth, for compensating for the loss of energy therein.

The measuring apparatus herein shown and described is claimed in my divisional application, Serial No. 45,743, filed July 24, 30 1925, for electrical measuring devices.

My invention is not limited to the particular systems illustrated, as it may be applied to various devices without departing from the spirit and scope of the invention, as set 35 forth in the appended claims.

I claim as my invention:

1. The combination with an electric circuit, of means connected to the circuit for permitting only currents having certain 40 characteristics differing from the characteristics of the main current to traverse the same and means responsive to the said currents for supplying energy to the circuit in accordance therewith.

45 2. The combination with an electric circuit, of means connected to the circuit traversed by currents having predetermined characteristics differing from the characteristics of the main current and means actuated in accordance with the said currents for supplying current to the circuit.

50 3. The combination with an electric circuit, of means connected to the circuit that is traversed by currents other than the main current in said circuit, and means for supplying current to said circuit in accordance with the currents traversing said means.

4. The combination with an electric circuit, of means connected to the circuit that is traversed by currents other than the main current in said circuit, and a series generator for supplying current to said circuit in accordance with the current traversing said means.

55 5. The combination with an electric cir-

cuit, of means connected to the circuit that is traversed by current other than the main current in said circuit, and independent electrical means for introducing energy into said circuit in accordance with the current 70 traversing the said first mentioned means.

6. The combination with an intelligence-transmission circuit, of means connected to the circuit and responsive to external disturbances for introducing energy in the 75 circuit that the intelligence-transmission current is precluded from being retarded by reason of the external disturbances.

7. The combination with an electric circuit 80 traversed by currents of a desired frequency and an undesired frequency, of means traversed by said currents of undesired frequency and inherently responsive thereto for supplying a proportionate amount of energy 85 to said circuit.

8. The combination with an electric circuit traversed by currents of a desired frequency and an undesired frequency, of means connected thereto and selectively responsive to the currents of undesired frequency, and booster means for inherently responding to the currents traversing said first-mentioned means and generating, at all times, an undesired-frequency voltage which is substantially equal and opposite to the resistance 90 drop encountered by the undesirable-frequency currents in said first-mentioned means.

9. The combination with an electric circuit 95 subject to variable currents, of a series-wound booster generator having its magnetic circuit made wholly of non-magnetic material.

10. The combination with an electric circuit subject to variable currents, of a series-wound booster generator having its magnetic 105 circuit made wholly of non-magnetic material, and means for driving said generator at a substantially constant speed.

11. The combination with a source of variable electromotive forces varying from zero to relatively small values, of a circuit including a translating device connected to said source, and means for, in effect, reducing the resistance of said circuit substantially to 115 zero, said means comprising a series-wound generator having its magnetic circuit made wholly of non-magnetic material.

12. The combination with a main circuit impressed with electromotive forces of a 120 predetermined frequency, of a parallel-resonant circuit comprising parallel-connected inductance and capacitance devices tuned to said frequency and connected in series with said main circuit, said resonant circuit including some resistance, and means for substantially neutralizing the resistance drop 125 in said parallel-resonant circuit.

13. The combination with a line carrying 130 desired currents and also currents of an un-

desirable frequency, of a series-resonant circuit comprising serially-connected inductance and capacitance devices tuned to said undesirable frequency and connected to parallel across said line to absorb all of said currents of said undesirable frequency. said resonant circuit including some resistance, and means for substantially neutralizing the resistance drop in said series-resonant circuit. In testimony whereof, I have hereunto ¹⁰ subscribed my name this 22nd day of Oct., 1917.

CHARLES LE G. FORTESCUE.
